DISPLAY BOX FOR WATCH BANDS OR THE LIKE

George F. Lyman, South Hadley, Mass.

Application October 1, 1956, Serial No. 43,150

Term of patent 14 years

(Cl. D80—5)

Fig. 1.

Fig. 2.

Fig. 3.

Fig. 4.

Fig. 5.

Fig. 6.

Fig. 1 is a perspective view of the display box for watch bands or the like showing my new design; Fig. 2 is a top plan view thereof;

Fig. 3 is a bottom plan view of Fig. 1; and Figs. 4, 5 and 6 are enlarged cross-sectional views taken on Fig. 2 along lines 4—4, 5—5, and 6—6, respectively, as shown.

I claim:

The ornamental design for a display box for watch bands or the like, as shown.
